UNITED STATES PATENT OFFICE.

GEORGE J. McVEY, OF LINCOLN, NEBRASKA.

DESIGN FOR A MUSICAL INSTRUMENT.

52,539.

Specification for Design.

Patented Oct. 8, 1918.

Application filed June 14, 1918. Serial No. 240,087. Term of patent 3½ years.

To all whom it may concern:

Be it known that I, GEORGE J. McVEY, a citizen of the United States, residing at Lincoln, in the county of Lancaster and State of Nebraska, have invented a new, original, and ornamental Design for Musical Instruments, of which the following is a specification, reference being had to the accompanying drawings, forming part thereof.

The figure is a perspective view of the instrument.

What is claimed is:

The ornamental design for a musical instrument, as shown.

GEORGE J. McVEY.

Witnesses:

I. F. SEARLE,
E. M. CLARK.
